UNITED STATES PATENT OFFICE.

HORACE Z. LANDON, OF NEWTONVILLE, MASSACHUSETTS.

CORE.

Application filed November 8, 1923. Serial No. 673,611.

To all whom it may concern:

Be it known that I, HORACE Z. LANDON, a citizen of the United States, residing at Newtonville, in the county of Middlesex 5 and State of Massachusetts, have invented certain new and useful Improvements in Cores; and I do hereby declare the following to be a full, clear, and exact description of the invention, such as will enable others skilled in the art to which it appertains to make and use the same.

The present invention relates to cores for wound goods and methods of making the same, and more particularly to cores which 15 are ultimately to form the central support for rolls of narrow fabric, tape and the like.

The usual method of manufacturing narrow rolls of wound goods, such as friction tape for example, consists in winding or 20 rolling a wide strip of the material on a long core and subsequently cutting transversely through the entire roll to form a number of narrow rolls of the desired trade widths. Because of its economy and simplicity, a rolled paper tube is ordinarily 25 used for the core. However, it has been found that the cutting operation causes small particles to be torn or flaked off from the main body of the core, these particles 30 being impressed during the continuation of the cutting operation into the end surface of the roll of fabric. This not only forms an unsightly product due to the ragged edge 35 exhibited by the core and the presence of the flakes in the ends of the roll, but also detracts from the efficacy of the tape, because if the tape is of an adhesive nature the particles are retained thereon when it is unwound.

40 According to the present invention the long core before having the material rolled thereon, is dipped into or impregnated with an agent which will avoid objectionable flaking of the core during the cutting operation. This agent may take a wide variety 45 of forms, but it is preferred to employ something in the nature of a wax, which serves its purpose not only through uniting and forming a bond between individual 50 fibres of the core, but also by providing lubrication for the knife or cutter. This last feature is of importance because it makes for simple and economical cutting of the core, increases the life of the cutter and

enables more cuts to be made by the same 55 tool.

In the accompanying drawings Fig. 1 is a longitudinal section of a roll of material wound upon a long core showing one of the narrower rolls severed from the main roll; 60 and Fig. 2 is an end elevation of one of the finished rolls.

The invention is herein described as embodied in the manufacture of rolls of rubberized fabric or friction tape. Referring 65 to Fig. 1, a central core 4, ordinarily about 40 inches long, consists of a tightly wound roll of paper which may be wound in a parallel, spiral, or helical manner, as is well known. In order to prevent flaking of the 70 core during the subsequent cutting operation, the core is then dipped in a hardening, stiffening or lubricating compound of a consistency to insure thorough impregnation of the compound into the fibres of the 75 paper. For this dip, it is preferred to use melted paraffin, which upon hardening, not only gives a solid homogeneous core, but also provides an efficient lubrication 80 for the cutting tool. After the removal of the core from the paraffin dip the core is allowed to cool to harden the paraffin, and is then wound with the treated fabric 85 to form a roll of the desired diameter. The completed roll is then mounted on a 90 mandrel and rotated at the proper speed, during which a cutter is pressed at successive points along the roll to cut the latter into a number of narrow finished rolls of tape, one of which is indicated at 8 in Fig. 95 1. The type of roll obtained from existing methods when the core is not impregnated, is illustrated in side elevation in Fig. 2, the flakes torn from the core being impressed by the tight frictional engagement 100 of the roll on the cutter into the ends of the roll, as indicated at points 10. When the core is impregnated with the paraffin as above described, this objectionable flaking or breaking down of the core is avoided, 105 because of the uniting of the fibres of the core, and also through the lubricating of the tool. Moreover, this action of bonding the fibres and layers of the core prevents the cutter from breaking down the inner wall of the core and leaving a loose flap when completed, as frequently occurs under existing methods.

Having thus described the invention, what is claimed is:

1. A package comprising a roll of material having a flat surface capable of being marred during the process of cutting said roll and a paper core, said core having been treated with an agent in such manner that flaking of the core is prevented when said package is cut to length. 35
  - 10 2. A package comprising a roll of material having a flat surface capable of being marred during the process of cutting said roll and a paper core, said core having been treated with an agent in such manner that 40 flaking of the core is prevented when said core is cut to length.
  - 15 3. A package comprising a roll of adhesive tape to which flakes of paper would adhere and a paper core, said core having 45 been treated with an agent in such manner that flaking of the core is prevented when 50 said package is cut to length.
  - 20 4. A package comprising a roll of adhesive tape to which flakes of paper would 55 adhere and a paper core, said core having been treated with an agent in such manner that flaking of the core is prevented when 60 said core is cut to length.
  - 25 5. A package comprising a roll of adhesive tape to which flakes of paper would adhere and a paper core, said core having
- been impregnated with paraffin, in such manner that flaking of the core is prevented when said package is cut to length.
6. A package comprising a roll of adhesive tape to which flakes of paper would adhere and a paper core, said core having been impregnated with paraffin in such manner as to render said core self lubricating, and flaking of the core prevented when the core is cut to length. 35
7. The method of making a narrow roll comprising a core on which is wound material to which flakes from the core would adhere, which consists in impregnating a core of paper in such manner as to render said core non-flaking and self-lubricating, winding said material on the core and cutting both the core and the material into narrow widths. 45
8. The method of making a narrow roll comprising a core on which is wound material to which flakes from the core would adhere which consists in winding a web of paper into tubular form with a parallel winding, impregnating said web with paraffin to render the same non-flaking and self-lubricating when the same is cut to length, winding on said core a web of said material and subsequently cutting the roll of material into short lengths. 55

HORACE Z. LANDON.
